ATTORNEYS.

UNITED STATES PATENT OFFICE.

FERDINAND DALLAS McMILLAN, OF ATLANTA, GEORGIA.

BOILER-CLEANER.

SPECIFICATION forming part of Letters Patent No. 783,301, dated February 21, 1905.

Application filed June 17, 1904. Serial No. 213,014.

To all whom it may concern:

Be it known that I, FERDINAND DALLAS Mc MILLAN, a citizen of the United States, and a resident of Atlanta, in the county of Fulton 5 and State of Georgia, have made certain new and useful Improvements in Boiler-Cleaners, of which the following is a specification.

My invention is an improvement in devices for use in cleaning steam-boilers or other closed receptacles and by which to blow out any accumulations of mud or other semisolid matter from the various parts of the boiler and to make it possible to reach corners and all other points in the boiler by water or other 15 liquid, sand, paints, dust, air, or other fluids as may be desired; and the invention consists in certain novel constructions and combinations of parts, as will be hereinafter described and claimed.

20 In the drawings, Figure 1 is a sectional elevation, parts broken away, of a device embodying my invention; and Fig. 2 is a detail section on about line 2-2 of Fig. 1.

By my invention I provide in the wall of 25 the boiler or other receptacle an opening in which a pipe for the introduction or withdrawal of the desired material is universally jointed, so that the inner end or nozzle of the pipe may be given any desired direction. In 30 the construction shown the wall A, which may be the wall of a boiler or other suitable receptacle, has an opening A', in which the universally-jointed devices operate. To the wall A, surrounding the opening A', I secure

35 what for convenience of reference I term the "frame-ring" B, which is held securely in place by rivets C and is threaded internally, as shown at B'. Within the ring B is secured the carrier leaving the ball-socket for the ball D. This 40 carrier is shown as composed of the two united sections E and F, the outer section E being threaded on its outer side at E' to engage the threads B' of the frame-ring B, and such outer section E being rabbeted on its inner 45 side at E" and receiving the annular rib F' on the section F, such section F having the face-flange F", which is secured by bolts G to the outer section E, as best shown in Fig. 1 of the drawings. At their inner sides the sections E 50 and F of the carrier are formed with a con-

cave surface d, which is ground, turned, or otherwise brought to fit the convex surface of the ball D, which fits within the carrier and may be turned in any desired manner in order to give the proper direction to the inner 55 end of the pipe for introducing or withdrawing the liquid or fluid used in cleaning the receptacle. By this construction the cleaning apparatus may be readily applied to the boiler or other receptacle.

60 The ball D has in its outer side a threaded opening D' and in its inner side a threaded opening D", receiving the outer and inner sections H and H' of the pipe for introducing and withdrawing the material. As shown, the 65 openings D' and D" are in alinement, and the sections H and H' may be brought to coincide at their meeting ends, as will be understood from Fig. 1. The section H' has the nozzle end I, and the section H is supplied with a 70 coupling J, by which the hose-pipe K may be coupled, as desired. This hose-pipe K is flexible, so it will permit the manipulation of the delivery-pipes by the turning of the ball in its shell or socket in order to properly direct 75 the inner end of the pipe, as will be understood from the dotted lines in Fig. 1. The carrier may be notched at 7 for engagement by a spanner-wrench or may be otherwise adapted to be turned in adjusting the same 80 into and out of engagement with the framing B in the use of the invention.

The mud from the boiler may be blown out by blowing steam against the walls of the 85 boiler from the nozzle I, and mud and the cleansing material may be withdrawn by applying suction to the pipe K by means of an air-pump or other device that will suck the material out through the nozzle and pipes H and K.

90 The invention is simple, easily applied, and will be found efficient for the purpose for which it is designed.

Having thus described my invention, what I claim as new, and desire to secure by Letters 95 Patent, is—

1. The combination substantially as herein described, of the wall or plate having an opening, the frame-ring secured to the plate surrounding such opening and threaded at its 100

inner side, the carrier composed of inner and outer sections secured together, the outer section being threaded into engagement with the frame-ring and such outer and inner sections being curved on their inner faces to form the ball-socket, the ball held in such socket and having threaded openings in its inner and outer ends and the pipe for introducing or withdrawing the material and having sections threaded in the inner and outer ends of the ball, substantially as and for the purposes set forth.

2. The combination of the wall, the frame-ring held to the wall, the carrier composed of sections held together and to the frame-ring

and having the curved opening forming the ball-socket, the ball held in said socket and the supply and delivery pipe sections connected with said ball, substantially as set forth.

3. The combination with a device for cleaning boilers and the like, of the ball, a carrier for the ball having a ball-socket receiving the ball and pipes screwed into the ball from the opposite sides thereof substantially as set forth.

FERDINAND DALLAS McMILLAN.
